Primary Examiner — Mark A Goodwin*(74) Attorney, Agent, or Firm* — Knobbe, Martens, Olson & Bear, LLP(57) **CLAIM**

The ornamental design for a planter, as shown and described herein.

DESCRIPTION

FIG. 1 is a top front perspective view of a planter.
 FIG. 2 is a top rear perspective view of the planter of FIG. 1.
 FIG. 3 is a bottom front perspective view of the planter of FIG. 1.
 FIG. 4 is a bottom rear perspective view of the planter of FIG. 1.
 FIG. 5 is a front view of the planter of FIG. 1.
 FIG. 6 is a left side view of the planter of FIG. 1.
 FIG. 7 is a rear view of the planter of FIG. 1.
 FIG. 8 is a bottom view of the planter of FIG. 1.
 FIG. 9 is a top view of the planter of FIG. 1; and,
 FIG. 10 is a right view of the planter of FIG. 1.
 All features in broken lines are for the purpose of illustrating environmental structure and form no part of the claimed subject matter.

1 Claim, 10 Drawing Sheets(56)
